UNITED STATES PATENT OFFICE.

THOMAS R. BROWN, OF SPARKILL, NEW YORK, ASSIGNOR TO THE WESTINGHOUSE AIR BRAKE COMPANY, OF WILMERDING, PENNSYLVANIA, A CORPORATION OF PENNSYLVANIA.

MANUALLY-OPERATED ELECTRIC COUPLING.

1,243,706.

Specification of Letters Patent. Patented Oct. 23, 1917.

Application filed April 10, 1914. Serial No. 331,000.

To all whom it may concern:—

Be it known that I, THOMAS R. BROWN, a citizen of the United States, residing at Sparkill, in the county of Rockland and 5 State of New York, have invented new and useful Improvements in Manually-Operated Electric Couplings, of which the following is a specification.

This invention relates to electric train line 10 couplings, and more particularly to that type in which a movable contact carrier is adapted to be projected to connect fixed contacts in counterpart couplings and thereby close corresponding train line circuits.

15 The principal object of my invention is to provide manually operated mechanical means for projecting the contact carrier of an electric line coupling of the above type.

The invention also has other objects and 20 advantages which will be apparent in the following more detailed description.

In the accompanying drawings; Figure 1 is a vertical longitudinal section of counterpart couplings for electric train line circuits 25 in the coupled position and embodying my improvements; Fig. 2 a similar section of a single coupling, showing the parts in normal release position; Fig. 3 a fragmentary section on the line *a—a* of Fig. 2; Fig. 4 an 30 enlarged detail view of the spring mechanism for the contact carrier; Fig. 5 a horizontal section of the coupling on the line *b—b* of Fig. 2; and Fig. 6 a transverse section on the line *c—c* of Fig. 2.

35 As shown in the drawings, the coupling may comprise a casing 1 containing a plurality of fixed contacts 2 arranged in a horizontal row and connected to corresponding train line circuits.

40 Mounted to reciprocate longitudinally within the casing 1 is a movable slide or contact carrier 3 having electrically connected contact bars 4 and 5 adapted upon projection of the contact carrier to connect corresponding fixed contacts 2 of counterpart 45 couplings and thereby close the several train line circuits between the cars of the train.

At each side, the contact carrier 3 is supported by guide members preferably composed of interlocked pipe sections 6, each section being cut to provide three projecting tongues having the outer ends 7 extended laterally to form shoulders adapted to interlock with corresponding shoulders of

the companion pipe section, as shown in 55 Fig. 4 of the drawings.

Within the pipe sections is a spring 8 and another spring 9 is coiled around the exterior of the pipe sections.

The spring 9 bears at one end against a 60 collar 10 screwed onto the end of one of the pipe sections 6 and the other end of the spring 9 engages a washer 11 secured to the inner end of the contact carrier 3.

According to my present invention, means 65 are provided for projecting the slide manually and mechanically, and for this purpose I preferably employ a pair of racks 12 secured to the under side of the contact carrier 3 and a pinion 13 meshing with each 70 rack. The pinions 13 are mounted on a shaft 14 transversely mounted in the casing 1 and the opposite ends of the shaft are each provided with an operating handle 15.

In order to lock the contact carrier 3 in 75 its projected position, a trip lever 16 is mounted in the rear of the casing 1 in position to engage a projecting lug 17 of the contact carrier when in projected position. Said lever 16 is mounted on a transverse 80 shaft 18 having bearings in the casing 1 and opposite ends of the shaft carry operating handles 19. A spring 20 is applied to the shaft 18 and acts on the lever 16 to yieldingly press the same toward the contact carrier. 85

Normally, the parts of the coupling are in the positions shown in Fig. 2. If a coupling between cars is to be made, the meeting faces of counterpart couplings are brought 90 into engagement and then one of the handles 15 is turned so as to rotate the shaft 14 and the pinions 13. The corresponding contact carrier 3 is thereupon projected into the counterpart coupling, displacing the contact 95 carrier therein and causing the connected contact bars 4 and 5 to electrically connect the fixed contact 3 of the counterpart coupling, as shown in Fig. 1 of the drawings.

Upon movement of the contact carrier to 100 the projected position, the trip lever 16 drops into locking position and thereby prevents the return movement of the carrier.

Uncoupling may be effected by turning one of the handles 19 so as to lift the trip 105 lever out of engagement with the lug 17, the springs 8 and 9 then operating to return the contact carrier to normal position.

It may be here explained that one of the pipe sections 6 is secured to the casing 1 at the rear and the other or movable pipe section extends into the contact carrier and engages the same near the forward end. When the contact carrier is projected, the washer 11 of the carrier acts to compress the spring 9, since the opposite end is held stationary by the movable pipe section 6, which is interlocked with the fixed pipe section. The contact carrier of the counterpart coupling which is retracted by the projection of the other carrier operates to compress the inner spring 8 by moving the movable pipe section 6 relative to the fixed pipe section, so that in the coupled position, the springs 9 of the projected carrier and the springs 8 of the retracted carrier are in a state of compression and thus act in uncoupling to return the contact carrier in the counterpart coupling to normal position.

If desired, fluid pressure means may also be provided for operating the trip lever 16, such as the construction shown in Fig. 3, in which an operating finger 21 is secured to the shaft 18. A vertically movable pin 22 bears on the finger 21 and said pin engages the end of a stem 23. The stem 23 is adapted to be operated by a piston 24 subject on one side to the pressure of a spring 25 and having a port 26 opening to the opposite side through which fluid under pressure may be admitted to the piston. It will be evident that by supplying fluid through the port 26 to piston 24, said piston will be operated and the pin 22 depressed to thereby actuate the finger 21 and trip the lever 16, so as to allow the projected contact carrier 3 to return to normal position.

The coupling may be suspended from the car coupler so as to have, in some degree, an independent coupling movement, and for this purpose the rear end of the coupling may be connected to the car coupler 27 (shown in fragment) by a central pivoted link 28 adapted to permit a longitudinal movement of the electric coupling relative to the car coupler. The forward end of the coupling is supported by bolts 29 secured to the car coupler 27, said bolts being loosely mounted in the electric coupling, as shown in Fig. 5, so as to permit a certain amount of longitudinal movement of the electric coupling with respect to the car coupler. Interposed between a lug 30 on the electric coupling and a portion of the car coupler 27 is a coil spring 31 which tends to yieldingly maintain the electric coupling in a slightly projected position. This spring may be mounted upon a stud slidably mounted in the lug, 30, and having a head bearing against the coupler, 27. The forward meeting end of the electric coupling may be provided with a gathering nose 32 and a recess 33 so arranged that the gathering nose

32 engages the recess 33 of a counterpart coupling in the act of coupling, for the purpose of bringing the counterpart couplings into proper register.

The relative longitudinal movement of the coupling permits adjustment of the coupling heads for variations in alinement and the like.

Having now described my invention, what I claim as new and desire to secure by Letters Patent is:—

1. In an electric train line coupling, the combination with a casing containing a plurality of fixed contacts connected to corresponding train line circuits, and a movable contact carrier having contacts, of mechanical means adapted to be manually operated for projecting said carrier to electrically connect the fixed contacts of counterpart couplings, a spring mechanism for resisting the outward movement of said carrier, and a locking device for holding the carrier in its projected position.

2. In an electric train line coupling, the combination with a casing containing a plurality of fixed contacts connected to corresponding train line circuits, and a movable contact carrier having corresponding contacts, of mechanical elements mounted in said casing for projecting said carrier to electrically connect the corresponding fixed contacts of counterpart couplings, a manually operated device outside said casing for actuating said mechanism, a spring mechanism for resisting the outward movement of said carrier, and a locking device for holding the carrier in its projected position.

3. In an electric train line coupling, the combination with a casing containing a plurality of fixed contacts connected to corresponding train line circuits, and a movable contact carrier having contacts, of a rack and pinion adapted to be manually operated for projecting said contact carrier to electrically connect the fixed contacts of counterpart couplings, a spring mechanism for resisting the outward movement of said carrier, and a locking device for holding the carrier in its projected position.

4. In an electric train line coupling, the combination with a casing containing a plurality of fixed contacts connected to corresponding train line circuits, and a movable contact carrier having contacts, of a rack mounted on said contact carrier, a pinion meshing with said rack, a manually operated handle for rotating said pinion to project said carrier and electrically connect the corresponding fixed contacts of counterpart couplings, a spring mechanism for resisting the outward movement of said carrier, and a locking device for holding the carrier in its projected position.

5. In an electric train line coupling, the combination with a casing containing a plu-

- rality of fixed contacts connected to corresponding train line circuits, and a movable contact carrier having contacts, of a rack mounted on said contact carrier, a pinion 5 meshing with said rack, a handle for rotating said pinion to project the contact carrier, a spring mechanism for resisting the projection of the carrier, and a locking device for holding the carrier in its projected 10 position.
6. In an electric train line coupling, the combination with a contact carrier adapted to be projected into a counterpart coupling to electrically connect the train line circuits, 15 of a spring mechanism for resisting movement of the contact carrier in opposite directions from normal position, comprising interlocked pipe sections and a spring for opposing relative movement of said pipe sections.
7. In an electric train line coupling, the combination with a contact carrier adapted to be projected into a counterpart coupling to electrically connect the train line circuits, 20 25 of a spring mechanism for resisting movement of the contact carrier in opposite directions from normal position, comprising pipe
- sections having interlocking tongues for limiting the relative movement in one direction and a spring for opposing relative movement 30 in the opposite direction.
8. In an electric train line coupling, the combination with a contact carrier adapted to be projected into a counterpart coupling to electrically connect the train line circuits, 35 of a spring mechanism for resisting movement of the contact carrier in opposite directions from normal position, comprising pipe sections movable in one direction with the contact carrier, a fixed pipe section, said 40 pipe sections having interlocking tongues to limit relative movement in the opposite direction, a spring for opposing movement of the movable pipe section, and a spring interposed between the movable pipe section and 45 the contact carrier for opposing movement of the carrier in one direction.

In testimony whereof I have hereunto set my hand.

THOMAS R. BROWN.
